UNITED STATES PATENT OFFICE.

BENJAMIN L. BAILEY, OF DANIELSONVILLE, CONNECTICUT.

DRAWING MECHANISM FOR SPINNING-MACHINES.

SPECIFICATION forming part of Letters Patent No. 439,339, dated October 28, 1890.

Application filed January 14, 1890. Serial No. 336,930. (No model.)

To all whom it may concern:

Be it known that I, BENJAMIN L. BAILEY, of Danielsonville, county of Windham, State of Connecticut, have invented an Improvement 5 in Drawing Mechanism for Spinning-Machines, of which the following description, in connection with the accompanying drawings, is a specification, like letters on the drawings representing like parts.

This invention has for its object to provide the lower front roll of the usual set of rolls of a spinning-machine with an adjustable bearing, whereby the right position of the front rolls with relation to the middle and back rolls 15 may be maintained, notwithstanding wear of the parts, as will be described. In practice, in ordinary spinning and drawing frames, the journals of the lower front roll after continued use cut into their bearings, so that it fails to 20 occupy the proper established position with relation to the middle and back rolls, and owing to such change the twist is more or less altered as to its uniformity. To overcome any 25 defects due to the wearing away of the journal of the lower front roll and the consequent descent of the periphery of the said roll, I have provided the journal thereof with an adjustable bearing.

Figure 1 in section and elevation represents 30 part of the frame of a spinning or drawing frame with a set of rolls thereon, the lower front roll being shown as mounted in an adjustable bearing. Fig. 2 is a top or plan view of one of the roller-stands with the rolls removed. Fig. 3 shows top, rear, and bottom views of one of the bearings for the lower front roll. Fig. 4 is a broken-out plan view on a small scale, showing one form of gearing for connecting the various rolls in the set; and 40 Fig. 5 is a diagram of the same form of gearing to rotate the rolls.

The frame A, the roller-stand B, the front rolls a a', the middle rolls b b', the back rolls c c', the saddles d d', the bearing f for the 45 journals of the middle and back rolls, the gear e, fast on the shaft of the lower front roll a and gearing into the intermediate e', mounted on a stud e², the pinion e³, fast to the said intermediate and engaging the gear e⁴, fast on 50 the lower back roll c, the gear e⁵ (shown by dotted lines in Fig. 5) at the opposite end of the lower front roll, the intermediate gear e⁶

engaged by it, the said gear being mounted on a stud e^x, (shown by dotted lines, Fig. 5,) the pinion e⁷, fast to the gear e⁶ and engaging the 55 gear e⁸, fast on one end of the lower middle roll b, are, or may be, all as is usual in spinning-frames.

Instead of the gearing shown for connecting together and rotating the various rolls 60 with the proper difference in speed, I may use any other well-known form of gearing.

The proper difference in speed having been established and the surfaces of the top rolls having been brought into proper position with 65 relation to the middle and back rolls, it is desirable and necessary for the best result that the said lower front roll maintain its established relative position so long as they continue to run; but this position varies as the journals 70 of the lower front roll wear away, for then the surface of the roll by descending occupies a lower position. To compensate for this change of position of the lower front roll, I have provided the journals of the lower front 75 roll with adjustable bearings, one of said bearings being shown in the drawings, there being a like bearing for each journal. Each bearing g is provided with an adjusting device h, shown as a screw (see Fig. 1) passed 80 up through a part of the stand B and acting against the under side of the bearing, rotation of the said screw adjusting the said bearing g vertically to compensate for any wear between it and the journal of the lower front 85 roll a, resting upon it. This provision for adjusting the bearing g enables the peripheries of the rolls to be kept at the same level entirely across the frame, to thus insure uniformity in results. 90

To prevent end or longitudinal movement of the bearing g, I provide it with a projection g', which enters a notch 4 (see Fig. 2,) in an upright or web m, and to enable the journal of the lower front roll to always be maintained 95 centrally with relation to the adjustable bearing g, I have concaved or beveled inwardly from its edges the upper side of the said bearing, as best represented at g⁵ in Fig. 1.

I do not broadly claim an adjustable bearing; but prior to my invention I am not aware that a front roll in a spinning or drawing frame has ever had a vertically-adjustable bearing. 100

I claim—

1. The roller-stand, the middle and back rolls, and the front rolls, combined with separate bearings for the lower front roll, gearing 5 to drive the said rolls, and adjusting devices to vertically adjust the bearings of the front roll, to operate substantially as described.
2. A roller-stand and the lower front roll having journals, combined with vertically-10 adjustable bearings for the said journals, the said bearings having concaved surfaces to receive the said journals, and adjusting devices for the said bearings, substantially as described.
- 15 3. The roller-stand having the upright or

web *m*, and the bearings for the lower front roll, the said upright and bearing being connected by a projection on one entering a slot on the other, as described, combined with an adjusting device for vertically adjusting the 20 said bearing, to operate substantially as described.

In testimony whereof I have signed my name to this specification in the presence of two subscribing witnesses.

BENJAMIN L. BAILEY.
